COULOMETRIC SYSTEMS

Edgar L. Eckfeldt, Ambler, Pa., assignor to Leeds and
Northrup Company, Philadelphia, Pa., a corporation of
Pennsylvania

Filed Aug. 25, 1960, Ser. No. 51,968
19 Claims. (Cl. 204—195)

This invention relates to coulometric systems of the type wherein a constituent in a sample solution is removed by the passage of current through the solution and has for an object the provision of an arrangement which is reliable in operation and in which the constituent-removal reactions are controlled by the potential maintained on the working electrode of the system.

In my Patent No. 2,621,671 there were disclosed and claimed coulometric systems in which the concentration of a constituent in a solution was varied by the passage of the direct current through the solution, the current flow to bring the constituent to an end-point then becoming a measure of the concentration of the constituent in the sample solution under test. The end-point was determined potentiometrically.

In accordance with the present invention, the potentiometric detecting instrument of my said patent need not be utilized. More particularly, use is made of the fact that electro-oxidizable or reducible substances present in the solution have their own characteristic values of potential at which they will commence to react to an electrode. Thus, a given substance may be removed or its state changed by establishing between a reference electrode and a working electrode a potential difference which will produce at the working electrode the characteristic potential for that given substance. By means of this transformation, its concentration in the sample solution can be determined in terms of the current required to produce the transformation.

An explanation of the reaction mechanism will bring out important principles on which the present invention is based and will make clear the uniqueness of the cell design features. When an electrode reaction takes place, there is a solution zone directly adjacent an electrode in which the concentration of the reacting substance becomes partially depleted as a result of electrolysis. The thickness of this solution zone is of the order of 0.010 to 0.015 inch or less. Reactive materials that lie in this zone are under the direct influence of the electrode by reason of a concentration gradient which causes diffusion of the material toward the electrode. Hence, materials in this zone will tend to react quantitatively with the electrode. Materials that are more remotely located in the solution, however, will probably not react quantitatively, since they must depend on some type of convection process to bring them into the reaction zone before they have an opportunity to react. Ensuring 100% reaction of remotely located materials is thus a serious problem in the operation of conventional coulometric cells.

From the foregoing, certain important design considerations are indicated. Thus, it is desirable to create strong convection currents in the solution. Doing this will prevent solution stratification and will cause the more remote parts of the solution to approach the electrode more closely. This favorable condition can be achieved in the cell by providing means to introduce forced agitation of the solution. Forced agitation can be accomplished in a variety of ways, as it is a purpose of the present invention to make clear.

Another important design consideration that follows from the above explanation of reaction mechanism is the desirability of arranging the cell construction so that only thin layers of solution will be in contact with the electrode. The cell can be designed so that the maximum

2

solution thickness throughout will not significantly exceed about 0.015 inch, the thickness of the diffusion layer. By doing this, the remote regions of the solution are eliminated altogether, and thus the restrictive step of bringing the materials to the close vicinity of the electrode is thereby avoided.

Although the above measures will improve the cell performance, they nevertheless will not be completely effective unless the area of the electrode is adequate. The 10 situation can be stated by saying that under optimum conditions a given element of the electrode surface will be able to support just so much rate of reaction and no more. If the sample solution overloads the electrode, the cell will not perform satisfactorily and reaction efficiency 15 will drop. It is therefore necessary to design the cell and electrode so that the electrode will present an extensive surface area to the sample solution, more than is just necessary to handle the influx flow rate of reactive material. An object of the present invention is to show how 20 this design objective can be achieved along with the other important factors that contribute to good cell performance.

In carrying out the present invention in one form there- 25 of and to assure conditions under which rapid and 100% reaction takes place in the transformation of the con- stituent from one state to a second state, there is provided a cell having a liquid space for a reference solution. A reference electrode is disposed within that space, and there is provided a flow channel of substantial length, at 30 least one section of which comprises porous wall structure having one face disposed for application thereto of the reference solution and the other extending lengthwise of the channel. Thus, the reference solution provides a current-conducting path from the reference electrode to a working electrode. The working electrode itself is pref- erably of extended surface area and may not only be co- extensive with the length of the flow channel, but may also have provisions for increasing the available surface area beyond that of the flow channel itself. Through 35 suitable flow connections, a sample solution is introduced into the flow channel, and electrical control means are adjusted to bring the potential of the working electrode relative to the reference electrode to within a range of values having a singular relation to the reaction potential 40 of the constituent present in the sample solution whose concentration is to be measured. By providing the extended area for the working electrode and by means of a flow channel in which the thickness of the solution layer in contact with the electrode surface is of a very low order, 45 the objective of producing a 100% reaction is achieved, and thus if the current be measured, there will be obtained an indication of the concentration of the constituent in the sample solution.

For further objects and advantages of the invention and 50 for a more detailed discussion of preferred embodiments thereof, reference is to be had to the following description taken in conjunction with the accompanying drawings, in which:

FIG. 1 diagrammatically illustrates a system and cell 55 embodying the present invention;

FIG. 2 is a broadside view of the flow channel and working electrode of the cell of FIG. 1;

FIG. 3 is an enlarged sectional view of a fractional 60 part of the flow channel;

FIG. 4 is a fractional view of a part of the cell of FIG. 1 and illustrates a solution-agitating means for the flow channel;

FIG. 5 is a graph useful in explaining the operation of 65 the invention; and

FIG. 6 illustrates a further embodiment of the invention, in particular a cell including two flow channels and

a common reference electrode and a common source of reference solution.

Referring now to FIG. 1, a regulated flow of a sample solution is supplied through a line 10 to a flow channel 11. As shown, the sample solution may be that of a liquid within a constant-head device 12 of the Mariotte type which, through a tube 13, provides a constant head on the liquid delivered to a valve 14. A capillary tube 15 in conjunction with the device 12 produces a regulated constant flow of the sample solution through the supply line 10 to the flow channel 11 forming a part of the cell 18.

As best shown in FIG. 2, the flow channel 11 has a tortuous path, that is to say, fluid entering from the inlet line 10 flows through an outer circular path 11a, thence 15 to a second inwardly spaced circular path 11b, and eventually through the innermost circular 11c to an outlet line 20. The flow channel is closed by means of porous wall structure 21. This wall structure forms not only a part of the wall structure of the reference-solution chamber but also part of the wall structure of channel 11. One face of the porous wall 21 is in communication with a reference solution 22 within the liquid space 23 and provides for transfer of that solution through the porous structure to the channel 11. There is thus formed a conductive path between a reference electrode 24 within the space 23 and a working electrode which in the modification shown in FIG. 1 comprises the conductive plate 25 within whose face there is formed the flow channel 11. More particularly, the flow channel 11 is milled into a metallic plate 25, preferably of gold. The metal electrode 25 is relatively thin and, accordingly, it is provided with a back-up member 26 which, in turn, is clamped against the porous member 21 by clamping member 27 having a plurality of fastening bolts 28 disposed about its periphery. The porous wall 21 may be of fritted glass or unglazed porous ceramic material.

The cell 18 is provided with a clean-out plug 29. Through a supply line 30, the reference solution can be supplied through a valve 31 to the liquid space 23. As shown, a stopper 32 for the cell 18 has an air vent 33. The reference electrode 24 may be of silver with a coating of silver chloride.

As has been mentioned, an objective of the present invention is a cell construction which will provide a working electrode that can be set at a predetermined desired value of potential with respect to a flowing sample solution in contact with it. It is desired that this objective be met even when measurement currents are flowing through the cell. The design must also take into account the dilutive effect caused by the flow of the sample solution through the cell. This can be achieved as in cell 18 by bringing a reference solution into close proximity with the region of the electrode reaction, throughout the full extent of the electrode solution interface. Since it is necessary to separate the sample solution from the reference solution to prevent intermixing, a porous material is interposed between them. This prevents mixing of the two solutions but provides an electrolytic conductive path between them. The porous ceramic plate 21 achieves this function in cell 18, but other forms of porous separators and electrode-solution arrangements can be used. It will be noted that in cell 18 the ceramic member forms a portion of the wall of the solution channel. In some cell designs the porous member may take the form of an extended tube and through which tube the sample solution passes in contact with a working electrode disposed within the tube.

The reference solution is able to maintain a constant potential when the cell is operated because of two important factors, as follows: (1) a reference electrode system 24 of constant potential is employed in the reference solution 22 and (2) the reference solution 22 is chosen to have good electrical conductivity thereby avoiding objectionable IR drop potentials that could otherwise

arise from the flow of cell currents. The seepage of reference solution into the porous structure 21 will keep the electrolytic conductivity of that member at a satisfactory level to avoid objectionable potential losses in the form of IR drops in that member. It will be noted that pipe 30 and valve 31 are provided so that the reference solution can be added to keep the solution at its proper level.

The reference electrode is chosen to maintain an essentially constant potential with respect to the reference solution, even when the current flows as a result of normal operation of the cell. The electrode is of the thermodynamically reversible type such as is used for reference electrodes in making measurements of pH. In the present case, however, sufficient area must be provided to avoid polarization effects arising from cell currents. The electrode 24 may be a sheet of silver metal 1 x 3 inches covered with a coating of silver chloride. The reference electrode potential, influenced by the changes in the composition of the reference solution, is maintained relatively constant. The cell design not only ensures an adequate supply of this solution but also by virtue of the shielding function of the porous separator plate protects against gross changes in reference solution composition.

The potential between the electrode 24 and the reference solution 22, as has been indicated, remains constant even with current flow through the cell. Accordingly, if the voltage as read on the voltmeter 41 is varied, there will be a corresponding change in the potential on electrode 25. Thus, the potential of the working electrode 25 may be set at any selected value corresponding with the reaction voltage needed for removal or change of state of the constituent to be measured.

For convenience, the potentials hereinafter given for the working electrode 25 are those which may be readily set on the scale of voltmeter 41. Where positive voltages are given, the working electrode 25 will be made positive and where negative voltages are given the working electrode 25 will be made negative.

In the operation of the system, the liquid space 23 will be filled with a reference solution and the valve 14 opened to admit the flow of the sample stream by way of inlet line 10 to the flow channel 11. After coursing through the flow channel of extended length, the sample solution will exit by way of the outlet line 20 and be discharged to drain as by way of line 34. It will be noted that the end of line 20 has an elevation approximating that midway of the cell. This contributes to the uniformity of flow. A switch 36 is then closed to apply between the reference electrode 24 and the working electrode 25 a potential of a predetermined selected magnitude. This potential is determined by the positions of contacts 37a and 38a relative to their associated resistors 37 and 38. These resistors and the associated contacts form a source of direct current supply from a battery 39 connected to them by way of a rheostat 40. The resistors 37 and 38 have resistances of a relatively low order, 100 to 200 ohms each, for flow of current through each of them of a magnitude many times the current flow between the electrodes 24 and 25. Thus, the resistors 37 and 38 with their adjustable taps provide means for the adjustment of the voltage applied to the cell terminals and hence the potential of the working electrode 25.

If the sample solution from vessel 12 includes iodide, such, for example, as might be present in salt solutions, the reference solution in cell 18 will be 2 Normal potassium chloride solution. For determination of the iodide present in the sample solution, the contacts 37a and 38a will be set to positions which will produce on a voltmeter 41 a reading of 0.67 volt. A voltage within the range of above about 0.6 and below about 0.7 will be satisfactory, since the voltages within this range singularly represent the characteristic value of the potential at which the iodide will react at the working electrode 25. The foregoing potential is in terms of the use of a silver, silver chloride electrode for the reference electrode 24. Tough the work-

ing electrode 25 has been described as of gold, it may be of other materials inert to the sample solution and to the iodide present therein. It should also be inert to the electro-oxidizing effects due to the applied potential differences.

With a sample solution flowing through the flow channel at the rate of one milliliter per minute and the sample solution comprising 1×10^{-4} N potassium iodide dissolved in 2 molar sulphuric acid, the cell current was approximately 0.16 milliamperes. This current flowing through a resistor 42 of the precision type produced a potential difference which through a reversing switch 43 is applied to a measuring instrument shown as a recorder 44. The resistance value of resistor 42 is chosen to give only small potential differences. Thus significant changes in the cell voltage caused by variations in the current being measured are avoided. The voltmeter 41 indicates the actual voltage across the cell electrodes and preferably is of the high-impedance vacuum tube type which draws negligible current in making the measurement. Thus is avoided an error in the cell current measurement that would otherwise occur. The recorder scale 44a may be calibrated directly in terms of the constituent (the iodide) content of the sample solution.

For other constituents, the concentrations of which are to be determined, the potentials applied to the electrodes 24 and 25 will be differently selected. Thus, for example, for the determination of iodine, the contacts 37a and 38a will be set to positions producing a reading on the voltmeter 41 of +0.06, though the permissible range here is relatively wide, as between -0.75 and +0.2.

In connection with the foregoing, the positive and negative voltages are in reference to the polarity on the conductor connected to the working electrode 25. Inasmuch as the foregoing range clearly shows the cell will be operative with zero voltage existing between the electrodes 24 and 25, it will be seen that an external source of current is not essential to the operation of the cell in all applications. More particularly, if the contacts 37a and 38a be moved to their right-most positions and thus effectively connected one to the other, the system will be operative for the determination of iodine in the sample solution. In that event, current will flow between electrodes 24 and 25 and through the external circuit including the series resistor 42 by reason of the reactions taking place at the electrodes 24 and 25. More particularly, the reaction occurring at the reference electrode will be as follows:

The reaction at the working electrode is:

From these reactions, it will be seen that electrons will be released or given off at the reference electrode 24, and electrons will be supplied to the reaction at the working electrode 25. Thus, the current flow in terms of the direction of flow of electrons will be from the reference electrode 24 through the external circuit and to the working electrode 25.

From the foregoing equations, it will be seen that the calibration may be made in terms of the magnitude of the electrolysis current and in accordance with the following equation based upon Faraday's law:

$$N = \frac{I}{96,500R} \quad (3)$$

where

N is the sample solution normality,

I is the electrolysis current, and

R is the flow rate of the sample solution in liters per second.

Now that the invention has been described in connection with two constituents, it is to be understood that the principles are applicable to the coulometric determination of a wide variety of materials and with differing

characteristic values of potentials for the working electrode.

For example, in the following table it will be seen that the characteristic values of potential may be selected for any one of a number of constituents whose concentration is to be determined:

Table I.—Typical cell voltages for coulometric reduction of various substances

10 Substance	Voltage
I ₂	+0.06
Cu ⁺⁺	-0.55
Pb ⁺⁺	-0.72
Cd ⁺⁺	-0.94
Zn ⁺⁺	-1.30

Table I gives a listing of typical cell voltages for coulometric reduction of a number of substances contained in chloride solutions. The values are predicated on using as the reference electrode 24 either a 2 N silver chloride electrode or a saturated calomel electrode. The 2 N silver chloride electrode is only about 0.025 voltage more negative than the saturated calomel electrode and this difference is not significant in the operation of cell 18. It should be realized that the tabulated values are approximate only, since the potential at which a substance reacts will be determined by particular conditions, especially by the anion content of the solution. Furthermore, in measuring a given substance good operation will occur over a moderate range of voltage. In the case of reductions, it is only necessary to be sure the voltage is more negative than the critical value for the substance to be measured and that it is not too negative so that interference occurs from a competitive coulometric reaction.

The same principle applies in the case of coulometric oxidations. For these, the voltage must be at least positive enough to initiate the desired reaction, yet not so positive as to initiate undesired reactions that take place at higher potentials.

The reference electrode 24, shown as a silver chloride electrode, may take the form of a saturated calomel electrode. Thus, the calomel electrode may be readily formed by a pool of mercury in a depressed lower portion of the cell 18 and with the conductor leading to the present reference electrode 24 extending into the pool of mercury. Above the mercury is placed a quantity of calomel. The reference solution would continue to be potassium chloride, but its concentration would be increased to about 4 N.

In the preferred form of the invention, the surface area of the working electrode 25 is increased or extended as by providing a roughened surface throughout the flow channel 11. Though this may be done in many ways, it has been found that a multiplicity of depressions formed by a center punch, and as illustrated in FIG. 3, materially increased the efficiency of the cell by increasing the surface area of the working electrode 25. It is to be understood that the surface area of electrode 25 may be increased by filling the tortuous passage with finely divided particles of uniform size and which may be in the form of pellets of the same material as the electrode. Thus, for example, the channel 11 may be filled with small pellets of gold. These increase the surface area and minimize any tendency of stratification of the sample solution during its flow through the channel 11.

In place of the particles and to increase the surface area, the channel 11 may have disposed therein metallic wool of the same material as the electrode 25. There can also be used a fine wire in the form of a helix which may extend through the tortuous path of the reaction zone formed by the channel 11. The increase in the surface area is by the disposition of material which, in respect to surface area relative to its mass, has a ratio corresponding with that of metallic wool and finely divided metallic particles.

Further in accordance with the invention, it is desired to produce some agitation within the flow channel 11 during the operation of the cell 18. This has been accomplished by applying a vibrator to the outlet tube 20, shown in FIG. 1 as a flexible tube. A vibrator acting on tube 20 causes small pulses of back pressure through the tube 20 into the channel 11, thus producing agitation of the liquid within that channel. There has been shown in FIG. 4 a preferred arrangement for producing agitation of the liquid within the flow channel 11. For example, a vibrator 45 operates through a rod 46, a diaphragm 47 one side of which forms a flexible wall of a channel passage 48 connecting with the flow channel 11. The to-and-fro movement of the diaphragm 47 produces throughout the flow channel 11 a to-and-fro movement of the liquid therein, thus increasing the efficiency of the operation of the cell.

Though in general it is preferred to utilize a flowing stream of the sample solution through the flow channel 11, nevertheless, the arrangement permits a batch type of operation. Thus, after the opening of the valve 14 and the filling of the flow channel 11, that valve may be closed and the operation initiated as before by closing the switch 36. For the batch type of operation, the recorder 44 will apply its output to an integrator 50. The integrator will provide a reading on its scale 50a corresponding with the integral with respect to time of the current flowing through the series resistor 42. Thus, the total current flowing between electrodes 24 and 25 will on the integrator produce an indication representative of the quantity of the constituent in the sample solution which has been removed.

There has also been emphasized the fact that the reaction zone formed by the tortuous path of the solution adjacent to electrode 25 contributes to the efficiency of the reactions which take place. Though the actual dimensions of the flow channel 11 are not critical, nevertheless, the thickness of the solution layer adjacent to the electrode should be maintained of a low order. For example, in one embodiment of the invention, the groove forming the flow channel 11 had the following approximate dimensions: width 0.25 inch and depth 0.015 inch. For width values above and below these dimensions there may be more or less metallic wool disposed throughout the flow channel. The tortuous path may range in total length from one foot to several feet. It will be desirable to maintain the area of the flow channel of the order from five square inches to ten or more, based on the assumption it has a smooth surface contour. The inclusion of metallic wool, helices of finely divided wire and metallic particles not only increase the electrode area but also prevent the formation of a laminar flow pattern of the solution. The introduction of eddies in addition to the agitation provided by the agitating means 45 promotes solution mixing and interchange of the solution at the electrode surface to maintain high the efficiency of the reactions.

As a specific example of the determination of iodine and with the arrangement described above, the flow rate was set at 2.1 milliliters per minute. The voltage on the voltmeter 41 was set to +0.06 voltage. The sample stream contained potassium iodide and iodine. The current was found to be 0.063 milliampere. Applying Equation 3

$$N = \frac{I}{96,500R} = \frac{0.000063}{96,500 \times \frac{2.1}{60 \times 1000}} = 0.000019 \quad (4)$$

This means the presence of iodine 1.9×10^{-5} Normal. Referring now to FIG. 5, there has been illustrated a graph 60 plotted with voltage as abscissae and current as ordinates. In the absence of any constituent in the solution from the vessel 12 of an oxidizable or reducible material there may be attained a flow of current with change of applied voltage to the working electrode 25

as represented by the broken line graph 61. This curve 61 shows substantially no change of current with voltage over a substantial range, a result which may be anticipated because no reaction is taking place at electrode 25. The later steep upswing of the curve 61 is indicative of a reaction at the higher voltages which takes place between the electrode 25 and the liquid in channel 11.

If it now be assumed that the sample solution in vessel 12 has two constituents present, then as the potential on electrode 25 is increased, the current flow will be that indicated by the curve 60. The constituent which reacts at the lower voltage is first removed from the sample stream. This occurs at a region of substantially constant current flow corresponding with a reaction voltage V_A representing the preferred voltage for establishing the reaction potential for constituent A. The current required for the removable of substance A from the solution will be the difference between the total current flow C_A at the voltage V_A and the residual current flow C_R . To remove the residual current, that current flowing in the absence of constituent A but with flow of liquid through the channel 11, the zero-adjusting knob 44c of recorder 44 is rotated to provide a zero reading on the recorder with flow of current of magnitude corresponding with C_R . In this manner there is taken into account the presence of the residual current and the manner in which that current is removed from the measurement.

If it is now desired to determine the concentration of substance B in the solution, the reaction potential V_B is set by contacts 37a and 38a of FIG. 1 on the working electrode 25. To remove from indication on recorder 44 of the residual current, now of magnitude C_{RA} , knob 44c of recorder 44 is rotated until the recorder reads zero with flow of current corresponding to the value C_{RA} . Thus, the recorder responds to the current $(C_B - C_{RA})$ to provide measurement of the concentration of constituent B in the sample solution. While the foregoing operation is feasible in instances where the concentration of substance A remains constant, problems arise when there is variation in the concentration of substance A. To remove this variable there may be utilized the modification of FIG. 6.

In FIG. 6 there is a reference electrode 24 common to two working electrodes 25a and 25b, each of which is provided with flow channels 11d and 11e closed by porous wall structures 21a and 21b. The sample solution enters through supply line 10 from suitable means for producing a regulated constant flow of sample solution in supply line 10. The contacts 37a and 38a are set to establish on electrode 25a the voltage V_A of FIG. 5. The current flowing between electrodes 24 and 25a will then be indicated on a measuring instrument such as an ammeter 65, the zero of which is adjusted to remove the residual current C_R from its indication. Thus, the meter 65 will indicate directly the concentration of constituent A in the solution.

Since constituent A is entirely removed or its state changed in flow channel 11 and regardless of whether or not its concentration may vary, it will be seen that while the meter 65 will respond to the foregoing changes, substance A in outlet line 20 will not be present in a form which will affect the measurement in the second reaction zone formed by the flow channel 11b. Thus, the sample solution with substance A removed or in a changed state will pass through reaction zone 11b for determination of the concentration of constituent B. The reaction potential V_B of FIG. 5 will be established for the working electrode 25b by suitable positioning of the contacts 37e and 37f of resistors 37d and 37c, these resistors being supplied by way of rheostat 40a and the battery 39a. An ammeter 66 set for a zero reading with a current flow corresponding to the residual current C_{RB} , FIG. 5, will then indicate the concentration of constituent B.

The residual current C_{RB} is of a lower order than the

residual current C_{RA} for the reason that in measuring constituent B in the same reaction zone with constituent A present the current flow will be high enough for removal of constituent A before measurement of the added current incident to removal of constituent B. However, when constituent A has been removed before entry into reaction zone 11e of the sample stream the current flow will be only that required for removal of constituent B plus the residual current C_{RD} .

Any two substances of the illustrative table above set forth may comprise substances A and B since each of the substances in that table have constituent potentials differing one from the other. By including a return ammeter 67 in the common return circuit there may be measured the sum of the concentrations of substances A and B in the sample streams. The zero reading of ammeter 67 is set to take into account the sum of the residual currents C_R and C_{RD} .

In some cases it will be desirable to provide for the addition of a liquid before making an initial measurement as well as after the removal of substance A. This can be readily done by providing supply lines 68 and 68a for the added substances which under the control of valves 69 and 69a will flow respectively into supply line 10 and into transfer tube 20.

The added material is useful, for example, when it is desired to convert combined chlorine to free iodine. This can be readily done by adding a small amount of potassium iodide solution to the sample stream.

In general, the choice of the solvent electrolyte forming the substrate, that is, the liquid comprising the sample solution in the absence of the constituent to be measured, offers the possibility of changing the potential values at which particular substances will react at an electrode. If it is desired to determine lead in the presence of +3 antimony contained in a hydrochloric acid solution, the antimony will deposit several tenths of a volt in advance of the lead and thereby make difficult the measurement. However, by utilizing a substrate solution comprising an alkaline tartrate medium, as for example, by adding a solution containing sodium hydroxide and sodium tartrate, as by opening valve 69, FIG. 6, the reaction potentials of the two substances, lead and antimony, will be reversed. The lead can then be measured with the potential of electrode 25a at around -1.1 volts, at which potential the antimony will not react. To measure the antimony, the potential at the electrode 25b will be made more negative, as for example, it can be set to about -1.6 volts, and the antimony will be removed. Thus, there has been set forth an example of how the arrangement of FIG. 6 will be utilized for substances A and B. It is to be understood that the two examples of lead and antimony may be sequentially determined in the arrangement of FIG. 1 and in manner already discussed in connection with other substances.

What is claimed is:

1. A coulometric system comprising a cell having a first liquid space for a reference solution, a reference electrode disposed within said liquid space, means including an electrolytically conductive member forming a second liquid space including a flow channel and having an electrolytic conductive path extending through said member, said member being disposed with one face exposed to said first liquid space and the other face thereof exposed to said second liquid space, flow connections for filling said channel with a sample solution having a constituent therein transformable by electrolysis from one state to a second state, said flow channel including a working electrode of large surface area maintained at a predetermined potential in contact with said sample solution for producing chemical reactions which transform said constituent from said one state to said second state to the exclusion of reactions at higher potentials of other constituents, said flow channel having maximum solution thicknesses with respect to said surface area of said working electrode of about

fifteen-thousandths of an inch, and means including current-responsive means connected to said electrodes for measuring the current flow incident to chemical reactions occurring at said working electrode which transform said constituent from said one state to said second state as a measure of the constituent content of said sample solution.

2. The coulometric system of claim 1 in which solution-agitating means are provided, means for coupling said agitating means to said flow channel for producing agitation of said sample solution during operation of the cell.

3. The coulometric system of claim 1 in which said flow channel is in the form of a tortuous passage.

4. The coulometric system of claim 1 in which said flow channel takes the form of a plurality of arcuate paths of differing degrees of curvature.

5. The coulometric system of claim 1 in which said flow channel has disposed therein electrode material of a form characterized in that its surface area relative to its mass has a ratio substantially the same as that of metallic wool and finely divided metallic particles.

6. The coulometric system of claim 1 in which said flow connections for said flow channel include a constant-flow device for producing a regulated constant flow of sample solution through said flow channel.

7. The coulometric system of claim 1 wherein adjustable potential shifting resistors are connected to said working electrode for selectively establishing at said working electrode a potential which can range from positive to negative relative to the potential of said reference electrode.

8. The coulometric system of claim 1 in which said first liquid space is filled with a reference solution of high conductivity differing from said sample solution, and wherein said reference electrode forms a constant-potential system in cooperation with said reference solution.

9. The coulometric system of claim 1 in which there is provided potential-adjusting means including an external circuit for producing at said working electrode a predetermined potential relative to said reference electrode for the establishment of a reaction potential at said working electrode of magnitude for the substantially complete removal of said constituent to the exclusion of reactions of other constituents in said sample solution having higher potentials of reaction.

10. The coulometric system of claim 1 wherein said means including said electrolytically conductive member is an extended tube through which tube said sample solution passes in contact with said working electrode.

11. The coulometric system of claim 1 wherein said electrolytically conductive member is a ceramic plate.

12. The coulometric system of claim 1 wherein said working electrode has an extended surface area comprising finely divided particles.

13. The coulometric system of claim 1 wherein said flow channel is filled with finely divided particles of the same material as said working electrode.

14. The coulometric system of claim 1 in which said electrolytically conductive member comprises porous insulating material.

15. The coulometric system of claim 14 in which said flow channel extends inwardly from a flat face of a metal plate forming said working electrode, and in which that other face of said electrolytically conductive member is flat and is disposed opposite to said flat face of said metal plate.

16. The coulometric system of claim 15 in which the surface area of said working electrode materially exceeds the surface area of a like flow channel of smooth-surface contour.

17. A coulometric system comprising a cell having a liquid space for a reference solution, a reference electrode disposed within said liquid space, an electrolytically conductive member having one face only exposed to said

liquid space for application thereto of said reference solution to establish an electrically conductive path to the opposite working face of said member, a working electrode of extended area having a working face in juxtaposition with said working face of said member, said working face of said working electrode having formed therein an elongated, tortuous, shallow, open-sided flow passage with its open side closed by said working face of said member to form an elongated flow channel, said flow channel having a maximum solution thickness with respect to said working face of said working electrode of about fifteen-thousandths of an inch, flow connections for filling said flow channel with a sample solution having a constituent the concentration of which is to be determined, an external circuit connected to said electrodes and including means for producing at said working electrode a predetermined potential relative to said reference electrode for the establishment of a reaction potential at said working electrode of magnitude for the removal from said solution of said constituent to the exclusion of reactions of other constituents in the sample solution having higher potentials of reaction, and means operable in response to the current required for said removal of said constituent for indicating the concentration of said constituent in said sample solution.

18. A coulometric system comprising a cell having a first liquid space for a reference solution, a reference electrode disposed within said liquid space, means including electrolytically conductive structure forming a second liquid space and a third liquid space in flow communication with each other and respectively forming a portion of a flow channel for a solution having constituents therein transformable by electrolysis from one state to a second state, said electrolytically conductive structure in the region of said second liquid space and in the region of said third liquid space having a face portion exposed to said first liquid space and having in each of said second liquid space and said third liquid space an opposing face portion respectively exposed to said second liquid space and to said third liquid space, working electrodes of large surface area, one disposed within said second liquid space and one within said third liquid space, said portion of said flow channel including said second liquid space and said third liquid space having maximum solution thicknesses with respect to said surface areas of said working electrodes of about fifteen-thousandths of an inch, external circuits extending between each working electrode and said reference electrode, and means for relatively adjusting the potentials of said working electrodes for removal in said second liquid space of one constituent and for removal in said third liquid space of a second constituent having a

higher characteristic potential than said one constituent.

19. A coulometric system comprising a cell having a first liquid space for a reference solution, a reference electrode disposed within said liquid space, means including electrolytically conductive structure forming a second liquid space and a third liquid space in flow communication with each other and respectively forming a portion of a flow channel for a solution having constituents therein transformable by electrolysis from one state to a second state, said electrolytically conductive structure in the region of said second liquid space and in the region of said third liquid space having a face portion exposed to said first liquid space and having in each of said second liquid space and said third liquid space an opposing face portion respectively exposed to said second liquid space and to said third liquid space, flow connections for producing a flow of said solution first through said second liquid space and then through said third liquid space, working electrodes of large surface area, one disposed within said second liquid space and one within said third liquid space, said portion of said flow channel including said second liquid space and said third liquid space having maximum solution thicknesses with respect to said surface areas of said working electrodes of about fifteen-thousandths of an inch, external circuits extending between each working electrode and said reference electrode, current responsive means included in each of said external circuits, and means for relatively adjusting the potentials of said working electrodes for removal in said second liquid space of one constituent and for removal in said third liquid space of a second constituents having a higher characteristic potential than said one constituent.
